COMBINATION BEAM AND SHORING CLAMP

William H. Clark, San Mateo, Calif.

Application October 31, 1951, Serial No. 254,109

4 Claims. (Cl. 105—369)

1

This invention relates to a clamp adapted to be employed on board ship either as a beam clamp or as a shoring clamp.

When it is desired to hoist or drag relatively heavy articles on board ship it is customary to 5 releasably secure a clamp to an overhead beam or girder and then fasten suitable hoisting equipment to such clamp. Such hoisting equipment may normally be secured to the beam clamp by means of a shackle, the pin of which is passed 10 through a suitable opening provided in the clamp.

When the overhead beam to which it is desired 15 to secure the hoisting equipment is a channel the above procedure is relatively safe and simple because the lower horizontally extending flange of the channel may be readily engaged and is generally strong enough to take a relatively heavy load. However, when the beam comprises a bulb angle the installation of a beam clamp becomes 20 more difficult and more subject to the danger of the clamp slipping or becoming loose and falling away from the beam. It will be understood in this connection that the lateral extent or width of the bulb of a bulb angle is never more than one half the width of the flange which secures 25 the angle to the adjacent deck or bulkhead. Usually the width of the bulb is only about one third the width of the flange.

One of the objects of the present invention is 30 therefore the provision of a clamp for use on board ship as a beam clamp and which clamp is particularly adapted to be releasably secured to a bulb angle beam.

The present invention is also adapted to be employed as a shoring clamp for releasably securing 35 one end of a tension strap adapted to be passed around a section of stowage on board ship. In this last mentioned application the clamp may be secured either to the overhead beams in a ship or to the generally vertically extending frame 40 members. In this respect the present invention has certain similarities to the clamp disclosed in my copending application for Letters Patent Serial No. 13,401, filed March 6, 1948, now Patent No. 2,609,761, September 9, 1952. However, as will subsequently be seen the present invention is particularly adapted to be employed 45 as a shoring clamp when the beams or frames to which the clamp is to be secured are bulb angles.

The main object of the present invention is 50 therefore the provision of a clamp which may be employed to releasably secure the ends of a tension strap for shoring storage when the available beams, frame members, or other stiffeners are bulb angles.

Another object of the invention is the provision 55 of a clamp adapted to be releasably secured to a bulb angle and which clamp will not loosen under load but on the contrary will become tighter.

Still another object of the invention is the pro- 60

2

vision of a clamp which may be releasably secured to a bulb angle and which will resist heavy loads regardless of the direction in which such loads are applied.

Yet another object of the invention is the provision of a clamp which is extremely compact, relatively light and readily handled by a workman.

Other objects and advantages will be apparent from the following specification and from the drawings. In the following description the clamp will be described with reference to use on board ship but it will be understood that the same may be similarly applied to aircraft, railroad cars and other vehicles.

Fig. 1 is a perspective view of the clamp assembly in closed position.

Fig. 2 is a perspective view similar to Fig. 1 but slightly reduced in size and showing the clamp in open position.

Fig. 3 is a cross-sectional view through a bulb angle and its associated deck or bulkhead with the clamp secured to said bulb angle. The clamp is shown in section.

Fig. 4 is a semi-schematic perspective view of a section of storage showing the clamp employed in various ways for securing the ends of the tension straps employed for shoring the storage.

In detail the invention comprises a pair of opposed jaws generally designated 1, 2 which are provided with gripping elements 3, 4 respectively adapted to engage the opposite sides of the web 5 of a bulb angle generally designated 6 (Fig. 3). The conventional bulb angle is formed with a flange 7 at right angles to the web 5 and adapted to be secured to a deck or bulkhead 8 as by rivets 9.

Along the edge of the web 5 opposite from the flange 7 is a bulb or rib 10 which projects laterally outwardly from the web 5 in the same direction as flange 7 but which is substantially deeper and narrower than said flange. The side 11 of said bulb along the outer edge of web 5 is perpendicular to the web 5 and the opposite side 12 of bulb 10 extends outwardly from the web 5 at an angle of 60° thereto so that the sides 11 and 12 are convergently disposed at an angle of 30° (Fig. 3). These sides 11, 12 are joined outwardly of the web 5 by a rounded juncture 13.

The gripping elements 3, 4 of jaws 1, 2 are rectangular and are preferably wider in a direction longitudinally of the bulb angle than they are deep so as to minimize any tendency of the clamp to cock with respect to the bulb angle. Integral 55 with the lower edge of the gripping element 3 is a portion 15 which is substantially a return bend having a straight section 16 adapted to engage the side 12 of the bulb 10 and which therefore extends from the gripping element 3 at an angle of 60°. The opposite end of the bend 15 is rigid

with the body portion of the clamp, said body portion being generally designated 20.

A pair of webs 21, 22, integral with the element 3 and the portion 15 and perpendicular thereto extend respectively from the opposite side edges of said element and portion and are made integral with the body portion 20 for resisting bending in jaw 3.

The body portion 20 is a relatively heavy section which extends transversely of the length of the bulb angle when the clamp is secured thereto. The body 20 extends to a point on the side of web 5 opposite element 3 a distance about equal to the depth of the curved portion 15 so that the center of the body portion 20 is substantially co-planar with the web 5 of the bulb angle 6. The end of body 20 opposite the curved portion 15 is provided with a stud 23 which extends outwardly from said body in a direction perpendicular to the plane of the web 5 of the angle.

Jaw 2 of the clamp is swivelly supported on stud 23 and a nut 24 on stud 23 serves to tighten jaws 1, 2 against the bulb angle 6. The construction of jaw 2 is very similar to that of jaw 1 in that a pair of webs 25, 26 extend outwardly from the opposite side edges of gripping element 4. However the portion 27 which extends outwardly from the lower edge of element 4 at an angle of about 60° is substantially longer than portion 16 of jaw 1 and is integrally secured at its lower end to a collar 28 which is apertured to receive stud 23. Webs 25, 26 are also rigidly connected to collar 28.

As best seen in Fig. 2, when the nut 24 is loosened on the stud 23 the jaw 2 may be swung through a right angle from its position of Figs. 1, 3 so that the jaw 1 may be placed against a bulb angle with the bulb of the angle received in the recess formed by the curved portion 15. Jaw 2 may then be swung upwardly into the position of Figs. 1, 3 and the nut 24 tightened. When the flat side 12 of the bulb 10 is engaged by the straight section 16 of portion 15 it will be apparent that the clamp will be firmly but releaseably secured to the bulb angle.

For the purpose of securing a connecting element to the clamp a hole 30 is formed in the body portion 20 extending in a direction longitudinally of the angle 6. This hole 30 is elongated in a direction transversely of the bulb angle for the purpose of receiving conventional tension strap which is quite wide in comparison with its thickness. Such a strap will be explained in greater detail later on.

When the device is employed as a beam clamp the shackle pin 31 of a shackle 32 may be passed through the hole 30 for securing said shackle to the clamp. Any desired hoisting equipment may then be secured to the shackle, Fig. 3.

Extending outwardly from the body 20 on the side opposite the jaws 1, 2 is a relatively wide eye member 34 providing a hole 35 substantially identical to hole 30 but extending in a direction at right angles to the latter. It will be apparent that tension straps which extend generally in a plane perpendicular to the bulb angle 6 may be passed through opening 34 while straps which extend generally in the plane of the bulb angle may be passed through opening 35.

The openings 30, 35 are positioned so that they are in the plane of the web 5 of the bulb angle 6 as seen in Fig. 3. In this manner the bending movement impressed on the clamp at the gripping elements 3, 4 is a minimum. Furthermore it will be apparent from the above described structure that hole 30 is positioned as closely as possible

to the bulb angle 6 which has the effect of further minimizing adverse bending effects.

In Fig. 4 a section of storage 40 is shown positioned on a deck 41 of a ship. Two intersecting bulkheads 42, 43 are also indicated along with an overhead deck 44. A pair of vertically extending bulb angle frames 45, 46 are secured to bulkhead 42 and similar bulb angle frames 47, 48 are secured to bulkhead 43. Bulb angle beam 50 is secured to the underside of deck 44.

Following conventional procedure steel straps 51, 52, 53 may be employed to secure the storage 40 in place against any tendency to shift during transit. These straps may be cut in suitable lengths and passed through holes 30 or 35 of the clamp and sealed by means of seals indicated at 54 in Fig. 4.

Clamp A is shown secured to the stiffener 48. Strap 51 may be passed through hole 30 of the clamp and then passed downwardly to the deck 41 and along the same. The cargo 40 may then be placed on deck 41 on top of strap 51 and the latter run upwardly along the side of the cargo and connected at its upper end to clamp B on beam 50 through hole 30.

Clamp B may also be employed to secure the upper end of a strap 53 which runs downwardly along an adjacent side of storage 40 and is secured to a clamp on stiffener 46 on bulkhead 42 in like manner to strap 51.

Clamp C is secured to stiffener 45 on bulkhead 42 and serves to receive one end of a horizontally extending strap 52 which may be passed through hole 35. Strap 52 may then extend along the adjacent outer sides of the storage 40 and then alongside bulkhead 43 to clamp A on stiffener 48 to which it is secured through hole 34.

When removing or installing storage it is a relatively simple matter to install the clamps shown in Fig. 4 inasmuch as no permanent means of securement to the beams and stiffeners is required. The provision of the two holes 30, 35 closely adjacent the bulb angle not only makes the clamp more compact but also minimizes the bending moments brought to bear on the beams and stiffeners and also on the gripping elements 3, 4.

The particular structure of the jaws 1, 2 hereinbefore described makes the clamp extremely stable at any angle of loading. For example in Fig. 3 it will be apparent that eccentric loading of the clamp as by strap 60 shown in Fig. 3 will cause the clamp to grip the angle tighter than when unloaded.

Likewise when the device is under direct loading as by the shackle 32 in Fig. 3 the portion 16 of the jaw will engage the flat side 12 of the bulb angle to prevent slippage. When straps are employed with hole 30 this last mentioned condition is also present.

The present invention may be employed on almost any bulb angle regardless of size because the difference between the bulbs of different sizes of bulb angles is substantially a difference in lateral extent only. In other words, with reference to Fig. 3, a smaller bulb angle than that illustrated will have a thinner web 5, but the depth of the bulb will be substantially the same as in the larger angle. From this it follows that the opposite sides 11, 12 of the bulb 10 will be firmly gripped by the straight section 16 and the body portion 20 of the clamping element 1. If the bulb angle is larger than that shown in Fig. 3, the space between the rounded juncture 13 of the bulb and the portion 15 of the jaw 1 is sufficient to receive the additional material present because of the

increased lateral extent. The increase in depth of the bulb of such a larger size bulb angle will be negligible.

Attention has already been called to the fact that hole 39 is as close as possible to the bulb 19 of the bulb angle 6, there being only the wall that defines the upper side of said hole between the two and said hole is also on the axis of bolt 23 and is substantially bisected by the plane of web 5 of the bulb angle.

The hole 35 is directly below hole 39 and is separated therefrom only by the lower wall of hole 30 which is also the upper wall of hole 35.

It is also to be noted that portion 27 and side 16 of jaws 2, 1 respectively are complementary in that they extend downwardly away from each other at the same angle and from the same level, hence the clamp may readily be secured to the bulb in a position opposite from that shown in Fig. 3 if the nut 24 is not accessible.

The inner sides of holes or openings 30, 35 are preferably substantially oblong in cross-sectional contour so that the side of each that is adapted to be engaged by a strap such as strap 60 will not distort the latter. The edges of the strap engaging sides of said holes or openings at the ends of each opening are rounded to prevent sharp bending of the strap. This contour of the openings does not interfere with the use of shackle 32 where desired.

I claim:

1. A combination beam and shoring clamp for use with a bulb angle having a flange adapted to be secured to a structure, a web extending at right angles to said flange and a bulb formed along the free edge of said web opposite said flange; said clamp comprising a pair of opposed jaws swivelly connected together and adapted to receive said web therebetween, means for tightening said jaws on said web with the opposed gripping surfaces of said jaws respectively engaging the opposite sides of said web, one of said jaws including a body portion extending transversely of said web and closely adjacent said bulb when said clamp is in clamped position on said angle, a pair of openings in said body portion extending at right angles to each other for receiving connecting elements therethrough for securing perpendicularly extending lines to said clamp, one of said openings being positioned closely adjacent said bulb and extending in a direction longitudinally of said angle and the other of said openings being spaced outwardly of said one opening along a line coplanar with said web, said means including an elongated threaded element carried by said body and generally coplanar with said one opening.

2. A combination beam and shoring clamp for a bulb angle comprising; a pair of web-clamping jaws adapted to clamp the web of said bulb angle therebetween, a pair of extensions respectively integral with said jaws extending divergently therefrom at substantially the same angle as that at which the surface of the laterally projecting bulb of said angle joins the web whereby one of said extensions may engage said surface when either one of said jaws is in engagement with the side of the web from which said angle projects, a body portion integral with one extension of said pair projecting across the plane of said web below said bulb when said jaws are in web gripping relationship with one of said extensions in engagement with said surface, a bolt and a nut connecting said body portion with the other extension of said pair for tightening said jaws against said

web and a pair of open ended holes formed in said body extending at right angles to each other with their axes intersecting at a point in said plane of said web along a line extending perpendicular to the direction of movement of said jaws and about midway between the ends of the latter.

3. A combination beam and shoring clamp for a bulb angle comprising; a pair of web-clamping jaws adapted to clamp the web of said bulb angle therebetween, a pair of extensions respectively integral with said jaws extending divergently therefrom at substantially the same angle as that at which the surface of the laterally projecting bulb of said angle joins the web whereby one of said extensions may engage said surface when either one of said jaws is in engagement with the side of the web from which said angle projects, a body portion integral with one extension of said pair projecting across the plane of said web below said bulb when said jaws are in web gripping relationship with one of said extensions in engagement with said surface, a bolt and a nut connecting said body portion with the other extension of said pair for tightening said jaws against said web and a pair of open ended holes formed in said body extending at right angles to each other with their axes intersecting at a point in said plane of said web along a line extending perpendicular to the direction of movement of said jaws and about midway between the ends of the latter, the axes of one of said holes being along the axes of said bolt.

4. A combination beam and shoring clamp for a bulb angle comprising; a pair of web-clamping jaws adapted to clamp the web of said bulb angle therebetween, a pair of extensions respectively integral with said jaws extending divergently therefrom at substantially the same angle as that at which the surface of the laterally projecting bulb of said angle joins the web whereby one of said extensions may engage said surface when either one of said jaws is in engagement with the side of the web from which said angle projects, a body portion integral with one extension of said pair projecting across the plane of said web below said bulb when said jaws are in web gripping relationship with one of said extensions in engagement with said surface, a bolt and a nut connecting said body portion with the other extension of said pair for tightening said jaws against said web and a pair of open ended holes formed in said body extending at right angles to each other with their axes intersecting at a point in said plane of said web along a line extending perpendicular to the direction of movement of said jaws and about midway between the ends of the latter, the side of each of said openings opposite to the side nearest said jaw being flat for engagement with a flat side of metal strap adapted to extend therethrough and the distance between the aforesaid sides being less than the other dimensions of said openings.
